his Atty.

UNITED STATES PATENT OFFICE.

CHARLES C. HARTUNG, OF ST. LOUIS, MISSOURI, ASSIGNOR TO EDWARD WALSH, JR., OF SAME PLACE.

DESIGN FOR SHEET-GLASS.

SPECIFICATION forming part of Design No. 27,322, dated July 13, 1897.

Application filed May 14, 1897. Serial No. 636,568. Term of patent 14 years.

To all whom it may concern:

Be it known that I, CHARLES C. HARTUNG, a citizen of the United States, residing at the city of St. Louis, State of Missouri, have made 5 a new and original Design for Sheet-Glass, of which the following is a full, clear, and exact description, reference being had to the accompanying drawings, forming part of this specification, wherein—

Figure 1 is a plan view of a small piece of glass made in accordance with my new and original design. Fig. 2 is a cross-sectional view through the same.

This invention relates to a new and original 15 design for sheet-glass; and it consists in the surface ornamentation thereof, as will hereinafter be more fully described.

In the drawings I have shown a small piece of glass, one surface of which is config-

ured according to my new and original de- 20 sign.

The design consists, essentially, of closely-associated tri-pointed figures, in the center of each of which is arranged a star or raised figure having lines emanating from a common 25 point. In the three corners of each figure of my design are raised curved ribs, as shown.

What I claim is—

The design for sheet-glass, substantially as herein shown and described.

In testimony whereof I have hereunto affixed my signature, in presence of two witnesses, this 7th day of May, 1897.

CHARLES C. HARTUNG.

Witnesses:

F. R. CORNWALL,
HUGH K. WAGNER.
